UNITED STATES PATENT OFFICE.

WILLIS J. PERKINS, OF GRAND RAPIDS, MICHIGAN.

SHINGLE-SAWING MACHINE.

SPECIFICATION forming part of Letters Patent No. 391,643, dated October 23, 1888.

Application filed February 27, 1888. Serial No. 265,377. (No model.)

To all whom it may concern:

Be it known that I, WILLIS J. PERKINS, residing at Grand Rapids, in the county of Kent and State of Michigan, have invented 5 certain new and useful Improvements in Shingle-Sawing Machines, of which the following is a specification, reference being had therein to the accompanying drawings.

This invention relates to shingle sawing machines; and it consists in certain improvements in the operative mechanism, substantially as hereinafter described.

The improvements are specially intended to apply to shingle-sawing machines heretofore 15 invented by Willis J. Perkins, but are in parts applicable to other machines.

The improvements are in the driving mechanism and in the tilt-operating mechanism.

In the drawings, Figure 1 is a side elevation 20 of so much of a double block shingle sawing machine as is necessary to show the present improvements, the right end of the machine being broken away and some parts omitted. Fig. 1^a is a side elevation of so much of the 25 frame and carriage as is necessary to show the operation of my tilt-driving device, and shows the cam-wheel and its pawl and the end of the walking-beam in elevation. Fig. 2 is an end view of part of the frame, carriage, and walking-beam and an end elevation of the cam-wheel and its friction-brake or retarder. Fig. 3 is a modified detail.

The frame and driving mechanism of the machine may be substantially such as shown 35 in my application, No. 204,635, filed June 9, 1886, to which application reference is made for a fuller understanding of the parts not herein described and claimed.

A indicates the frame of the machine. B 40 denotes the sideway, on which the bolt-carriage C reciprocates. C is a bracket attachment to said carriage, to which rod D is pivoted, said rod connecting to a swing-bar, E, pivoted at the center of the race-cam F, but 45 free to move independently of said cam-wheel. The cam-wheel F has a cam-race, G, with a central star-plate, H, surrounding rim I. Between rim I and star-plate H the race G is of such width as to receive the anti-friction roll K and hold it with a practically uniform bearing on both sides of said roll. The swing-bar

E has a pawl, L, pivoted to its outer end, in position to engage the teeth M of the cam-wheel. The forward movement of carriage C in the direction of the arrow moves the rod D, 55 and thus carries the pawl into one or the other of the ratchet-teeth. The backward movement of the carriage moves the cam-wheel by the engagement of the pawl L with the teeth M. The pawl N, pivoted to the frame, engages the 60 ratchet-teeth to prevent the movement of the cam-wheel in reverse direction.

The friction-roll K is at the end of walking-beam O, which is pivoted to the frame at Q and carries risers, (one being shown at R,) 65 which serve to tilt the table. This tilt-table is old, and equivalent mechanism for actuating the same may be substituted.

The race cam-wheel F is journaled at its center, to rotate intermittently under the impulse 70 of the pawl L. At the front of this wheel and bearing on its rim there is a friction-presser, S, which is preferably a bent spring-piece attached to the frame at T, and held toward the cam-wheel by set-nuts U U', engaging a 75 threaded bolt, V, extending out from the frame. The nuts U U' can be adjusted to apply any desired pressure to the face of the cam-wheel. The effect of the brake or presser S on the cam-wheel is to check the movement thereof the instant the pawl stops its movement. This pawl movement is so timed that the wheel K is in 80 the position in the cam-race which is necessary to give the proper tilt to the table the instant the carriage comes to a rest in its backward 85 movement. The friction-presser S may be duplicated and applied to both sides of the cam-wheel. A rim may be cast and turned up on the face of the wheel to give a proper and uniform bearing.

The rod D is adjustably connected to bracket C by a bolt, C², which bolt passes through any one of the holes C³ in said bracket. Thus the rod D can be adjusted to have just such movement as will carry the swing-bar E and pawl F just far 95 enough to move the race-cam a sufficient distance to tilt the table. The reciprocation of carriage C causes the tilt-table to move. This carriage is driven by oscillating levers a, connected to wrist-pins b by slides c on gears d, 100 as in the application referred to. The gears d are driven by a belt and train of mechanism

from the saw-arbor *e*. The saw-arbor *e* is supported in bearings, as usual in this class of machines. Usually, however, the driving-belt engages a pulley at about the point *f*, and in order to convey power to the machine this belt enters the frame at one side. In fact, as heretofore constructed it was impossible to carry power to the machine from the direction of the end which has the carriage-driving gear, and as the spalts, shingles, and sawdust must be separately conveyed away from the machine it was frequently a matter of much expense and inconvenience to locate the machine with reference to the engine, so that it could be used, the prevailing practice heretofore being to place machines of this class in the second story of the mill-building. This objection I overcome by extending the arbor below the bottom of the frame *A*, as at *g*. The machine can thus be set with the main driving-pulley below the mill-floor and receive a belt from any direction, while at the same time the conveyers above the floor can be located to suit the convenience of the particular mill in which it is desired to use the machine. The same arbor-box and cross-girt heretofore used is carried down to *h*, and there supported on bracket *i*—one bracket on either side of the machine—and suitably fastened to the frame. The belt can thus be brought in at the end of the machine without interfering with any of the working parts or of the delivery of the shingles at the side of the machine.

In the foregoing specification I have described the best mode now known to me for applying the principle of my invention; but changes, substitutions, and omissions may be made as regards subscribed parts, provided

only the essential elements of invention set forth in the following claims are employed. 40

What I claim is—

1. In a shingle sawing machine, the combination, with the tilt-table and its oscillating lever, of a cam-wheel in operative engagement with said lever, and a retarding-brake bearing on said cam-wheel, substantially as described. 45

2. The combination, with the tilt-table and its walking-beam, of a cam-wheel operatively engaging said walking-beam, and an adjustable presser bearing on said wheel to operate as a brake-retarder, substantially as described. 50

3. The combination, with the tilt-table of a shingle-sawing machine, of a lever for operating the same, a race-cam engaging said lever to move it positively in both directions, and a spring-presser bearing on the surface of said race-cam with an adjusted pressure, substantially as described. 55

4. In a shingle-sawing machine, a frame, an arbor vertically supported in said frame and a saw thereon, a pulley on the arbor below the saw for driving the carriage, an extension of the arbor below the supporting-legs of the frame, and a pulley on said arbor below the level of the bottom of the legs of the frame, and brackets connected to said frame and supporting the arbor below the bottom of said legs, all substantially as described. 60

In testimony whereof I affix my signature in presence of two witnesses.

WILLIS J. PERKINS.
